(57) **CLAIM**

The ornamental design for a cuff, as shown and described.

DESCRIPTION

FIG. 1 is a perspective view of the cuff showing the new design;

FIG. 2 is a left elevation view thereof;

FIG. 3 is a right elevation view thereof;

FIG. 4 is a top plan view thereof;

FIG. 5 is a bottom plan view thereof; and,

FIG. 6 is a perspective view of the cuff on a wearer's leg. The broken lines on the cuff in FIGS. 1-6 depict portions of the cuff and form no part of the claimed design. The broken lines showing a wearer's leg and foot in FIG. 6 depict environmental structure and form no part of the claimed design.

1 Claim, 5 Drawing Sheets
